UNITED STATES PATENT OFFICE.

FRANK H. ARMSTRONG, OF AUBURN, NEW YORK, ASSIGNOR TO CORONA TYPEWRITER COMPANY, INC., OF GROTON, NEW YORK, A CORPORATION OF NEW YORK.

TYPEWRITING MACHINE.

Application filed November 16, 1918. Serial No. 262,828.

To all whom it may concern:

Be it known that I, FRANK H. ARMSTRONG, a citizen of the United States of America, and a resident of Auburn, county 5 of Cayuga, State of New York, have invented certain new and useful Improvements in Typewriting Machines, of which the following is a full and clear specification.

10 This invention relates to that class of paper-feeding devices broadly covered by my copending application Serial No. 256,195, filed September 30, 1918, and the present improvements relate to devices for supporting the feed-roll shafts and releasing the feed-rolls from the platen, as more fully hereinafter set forth.

In the drawings—

20 Fig. 1 is a view partly in plan and partly in horizontal section of so much of a platen-carriage as is necessary to show my present improvements;

Fig. 2 is a transverse vertical sectional view on the line 2—2 of Fig. 1;

25 Fig. 3 is a vertical longitudinal sectional view taken on the lines 3—3 of Fig. 1;

Fig. 4 is a section taken on the line 2—2 of Fig. 1 showing the rear feed-rolls withdrawn from the platen;

30 Fig. 5 is a similar view showing both the front and the rear feed-rolls withdrawn from the platen;

Figs. 6, 7, 8, 9 and 10 are detail views hereinafter described;

35 Fig. 11 is a detail view showing a modification hereinafter described;

Figs. 12 to 18 are detail views of other modifications.

40 Referring to the drawings annexed by reference-characters, 15 designates a platen-carriage provided at each end with an up-standing flange 16 in which the ends of the shaft 17 of the platen 17 are journaled in the usual manner.

45 Extending between the end-flanges 16, the full length of the carriage, is a rock-shaft 18 whose ends are journaled in said flanges 16. This shaft is located behind the platen, at a point about on a horizontal level with the under face of the platen. This shaft is

provided with four forwardly-extending arms 19, and in holes formed in the forward ends of these arms are journaled the two rear feed-roll-shafts 20, each carrying a pair of feed-rolls 22 loosely mounted on the shaft and spaced apart by a loosely-mounted sleeve 23. The arms 19 are attached to the rock-shaft 18 by each having its rear end formed into an arch 24' whose depending members 24 are provided with holes for the 55 passage of said shaft, each of these members 24 being provided at its lower end—that is, at a point under the shaft 18—with a lateral lug 25 lying in a notch 26 formed in a collar 27 affixed to the shaft alongside 60 the member 24 by means of a set-screw 28,

The two feed roll front shafts 29 each carry a pair of feed-rolls 30 loosely mounted on the shaft and spaced apart by a loose sleeve 31, the ends of each shaft being journaled 70 in upstanding lugs 32 formed integral with the forward ends of a pair of transverse bars 34. The forward ends of these bars 34 are provided with upstanding stop-lugs 35 which prevents undue endwise movement of 75 the shafts 29. The rear ends of the end-bars 34 pass rearwardly under the rear shaft 20 and have their rear ends bent upwardly and rearwardly and downwardly to form a hook 36 which is engaged over the rock-shaft 18 80 to thus tie the end-bars and the front shafts 29 to the rock shaft. These hooks engage the shaft at a point between the arch-members 24 and are thus prevented from undue lateral movement on the shaft; and there is sufficient space between the shaft 18 and the top (24') of the arch to permit the rear-ends of the bar 34 to have a limited vertical play independently of the rear feed-rolls 22.

Formed integral with each arm 19 90 is a lateral lug 37 which engages the upper face of the adjacent one of the bars 34. Shaft 18 may be forwardly rocked in any suitable manner; I prefer the means illustrated in my aforesaid copending application, which consists in affixing to one end of the rock-shaft a forwardly-extending arm 38 and providing a cam-lever 39 (pivotally mounted on the platen-shaft 17') provided with two stop-faces 40 and 41 adapted to 95 100

alternately engage the upper edge of the arm 38, said arm 38 being normally drawn upwardly to thereby hold the rock-shaft and its connected parts in normal, working, position by means of a coil-spring 42.

Any suitable means may be employed to resiliently and uniformly press upwardly against the transverse bars 34 to thus keep the feed-rolls against the work on the platen; for instance, I may employ the devices shown in my aforesaid copending application, consisting of two longitudinal bars 43, each bar being pivotally supported upon and interlocked with a rockable plate-like yoke-member 44 pivotally mounted upon the top of the platen-carriage, these rockable members being normally pressed upwardly (to thereby constantly press bars 43 against the under side of end-bars 34) by means of a coil-spring 45 arranged at the rear of the rock-shaft 18 and connected to upstanding arms 46 mounted at the rear ends of the rocking plates.

It will be observed that when the release cam-lever 39 is swung rearwardly to thus bring its stop-surface 41 into engagement with the arm 38, the rock-shaft 18 will be in position to hold the arms 19 in a substantially horizontal position, in which position both feed-rolls will be in contact with the work on the platen, the bars 34 will be pressed upwardly against the lugs 37 and the hooks 36 will be held lightly in engagement with the under side of the members 24'. When the lever 39 is manually swung forward to depress the arm 38 and bring the cam surface 40 into position for locking relation with this arm 38, the successive movements of the parts will be as follows: The rear rolls 22 will be swung downwardly about the axis of the rock shaft away from the platen, and the bars 34 carrying the hooks 36 will be swung simultaneously downwardly against the action of spring 45 about the axis of the front feed roll shafts until these hooks engage the top-side of the rock-shaft; and then further rotation of the rock-shaft in the same direction will swing arms 19 and the rear rolls 22 farther from the platen and cause the lugs 37 to continue to press upon the upper sides of the end-bars 34 and thus, in the manner of a knuckle-joint, swing simultaneously down the forward ends of said bars and take the front rolls away from the platen, said bars swinging in unison with the arms 19 about the axis of the rock shaft, the parts being held in this off position by the stop-face 40 of the release lever, as shown in Fig. 5.

It will be observed that all the feed-rolls are normally held against the platen by the spring-means which forces pressure-bars 43 upwardly; this spring-means in the present instance is a single spring 45, but it will

be understood that the arrangement for this purpose shown may be greatly varied without departing from the present invention. It will be observed further that each pair of feed-rolls, whether front or rear, may yield away from the platen without releasing the remaining rolls, thereby enabling the rolls to automatically compensate for variations in the platen surface as well as for variations in the thickness of paper. It will be seen also that the construction described ensures alinement between the axes of both the front and rear feed-roll-shafts and the surface of the platen, while at the same time all undesirable floating action of the feed-rolls is entirely avoided.

In the modification shown in Figs. 12, 13 and 14, it will be observed that instead of the hook 36 I connect each of the bars 34 to the rock-shaft by means of a pair of upstanding ears 52 adapted to fit between the arch-members 24, these ears being provided with holes through which the rock-shaft 18 extends and these holes being vertically elongated to permit the necessary lost-motion or play between the bars 34 and the rock-shaft. In this modification, the arch-members 24 extend rearwardly instead of upwardly, so that the connecting arch-member (24') lies at the rear of the rock-shaft.

In the modification shown in Figs. 15 and 16, the hooks 36 are employed, but the vertical limitation of movement of the bars 34 is obtained by providing the depending end of the hook with lateral lugs 53 which engage under the arch-members 24; while in the form of device shown in Figs. 17 and 18, the upward movement of the rear-ends of the bars is restricted by means of a lug 54 extending rearwardly far enough to engage the under side of the arch-member 24'. It will be observed from the foregoing that the lost-motion knuckle-joint connection between the rear ends of the bars 34 and the actuating rock-shaft may be greatly varied without departing from the spirit of my invention.

The rear feed-roll-shafts may be held against undue endwise movement in substantially the same manner as the front shafts are held, these front shafts being desirably held against endwise movement by means of upwardly-bent ears 35 on the forward ends of the bars 34; for instance, one of the arch members 24 may be provided with an ear or lug 50 extending forwardly far enough to form an abutment for the adjacent end of the shaft 20, or the top member 24' which connects these members 24 may be provided with a forwardly-extending lug 51, as shown in Fig. 11, or as shown in Fig. 13 the lug 37 may be turned upwardly to form a stop-lug 52'. It will be further desirable that the lugs 25 shall have a slight lost-motion in the notches 26 in the collars 27 in order that the rear rolls may yield away from

the platen a limited distance without rotating the rock-shaft 18, as shown more particularly in Fig. 10.

The nature and scope of the invention having been thus indicated and its preferred embodiment having been specifically described what is claimed as new is:

1. In a paper feed mechanism, the combination of a platen, a cast-off rock-shaft extending longitudinally of the platen, means for rocking said cast-off shaft, a pair of tandem feed-roll shafts, feed-rolls on said tandem shafts, independent supports for the front and rear feed-roll shafts extending forwardly from the cast-off shaft, connections between the rear ends of said supports and the cast-off shaft whereby either roll-shaft may move away from the platen independently of the other while the cast-off shaft is stationary, and means whereby first one and then both of said shaft supports is rocked away from the platen about the axis of the cast-off shaft when the cast-off shaft is rocked in one direction.

2. In a paper feed mechanism, the combination of a platen, a cast-off rock-shaft extending longitudinally of the platen, means for rocking said cast-off shaft, a pair of tandem feed-roll shafts, feed-rolls on said tandem shafts, independent supports for the front and rear feed-roll shafts extending forwardly from the cast-off shaft, connections between the rear ends of said supports and the cast-off shaft whereby either roll-shaft may move away from the platen independently of the other while the cast-off shaft is stationary, means whereby first one and then both of said shaft supports is rocked away from the platen about the axis of the cast-off shaft when the cast-off shaft is rocked in one direction, and spring-urged means common to both shafts for yieldably forcing the shafts toward the platen.

3. In a paper feed mechanism, the combination of a platen, a cast-off rock-shaft extending longitudinally of the platen, means for rocking said cast-off shaft, a pair of tandem feed-roll shafts, feed-rolls on said tandem shafts, independent supports for the front and rear feed-roll shafts extending forwardly from the cast-off shaft, connections between the rear ends of said supports and the cast-off shaft whereby either roll-shaft may move away from the platen independently of the other while the cast-off shaft is stationary, and means for yieldably holding the rolls on one feed-roll shaft against the platen through the medium of the other feed-roll shaft support.

4. In a typewriting machine, the combination of a platen carriage, a platen rotatably mounted on the carriage, a manually operable cast-off rock shaft journalled on the carriage, a rear feed roll, supporting means for the rear feed roll pivotally held to the

rock shaft, a front feed roll, supporting means for the front feed roll having an up-and-down lost-motion pivotal connection with the rock shaft and engaging the under side of the rear feed roll supporting means, means for yieldably urging the roll supporting means toward the platen, and means rigidly held to the rock shaft engaging the rear feed roll supporting means for successively casting off the rear and front feed rolls when the rock shaft is rotated in one direction.

5. In a typewriting machine, the combination of a platen carriage, a platen rotatably mounted on the carriage, a manually operable cast-off rock shaft journalled on the carriage, a rear feed roll, means for supporting the rear feed roll from the rock shaft to have a limited movement toward and from the platen independent of rotation of the rock shaft and to swing away from the platen about the axis of the rock shaft when said shaft is rotated in one direction, a front feed roll, supporting means for the front feed roll pivotally connected with the rock shaft and adapted to be engaged and rocked about the axis of the rock shaft by the rear feed roll supporting means to cast-off the front feed roll, and means common to both feed rolls for yieldable pressing the feed rolls toward the platen.

6. In a typewriting machine, the combination of a platen carriage, a platen rotatably mounted on the carriage, a cast-off rock shaft journalled on the carriage, front and rear feed rolls, independent supports for the feed rolls carrying the feed rolls adjacent their forward ends, connections between the rear ends of said supports and the rock shaft whereby either feed roll may swing away from the platen independently of rotation of the rock shaft, spring means common to both feed rolls for pressing the same toward the platen, and means on the rock shaft for swinging the rear feed roll and its support away from the platen about the axis of the shaft, the support for the rear roll being adapted to swing the support for the front roll about the axis of the rock shaft during the final portion of its cast-off movement.

7. In a typewriting machine, a platen carriage, a platen rotatably mounted thereon, a rock shaft journalled on the carriage, means for rocking said shaft, rock arms on the shaft, a rear feed roll supported by said rock arms, a front feed roll, members supporting said front feed roll having lost-motion pivotal connections at their rear ends with the rock shaft and engaging under the rock arms, and means for yieldable pressing the members toward the platen.

8. In a typewriting machine, a platen carriage, a platen rotatably mounted thereon, a rock shaft journalled on the carriage,

- means for rocking said shaft, rock arms on the shaft, a rear feed roll supported by said rock arms, a front feed roll, members supporting said front feed roll having last-motion pivotal connections at their rear ends with the rock shaft and engaging under the rock arms, and means for exerting a uniform pressure on said members intermediate the front and rear feed rolls.
- 10 9. In a typewriting machine, the combination of a platen carriage, a platen rotatably mounted on the carriage, a cast-off rock shaft journalled on the carriage, means for rocking said cast-off shaft, two pairs of supporting members of different length extending in the same direction from the rock shaft, connections between one end of said members and the rock shaft whereby when the shaft is rocked in one direction the 15 shorter pair of members will swing with the shaft away from the platen and then press the longer pair of members away from the platen during the final portion of the movement of said shorter members, parallel feed 20 roll shafts journalled in said pairs of members adjacent the free ends of the members, feed rolls on said shafts, and means on the carriage controlled by a single spring for urging both pairs of members toward the 25 platen.
- 10 10. In a typewriting machine, a platen carriage, a platen rotatably mounted on the carriage, a manually rockable cast-off shaft journalled on the carriage, tandem feed roll 30 shafts, rolls on said shafts, independently supporting means for the feed roll shafts pivotally held at one end to the cast off shaft and extending in the same direction from the shaft, means on the rock-shaft 35 adapted when the shaft is rotated in one direction to engage and rock the supporting means for one feed roll shaft away from the platen and cause said supporting means after the roll supported thereby leaves the 40 platen to lock the other roll shaft supporting means to the rock shaft and thereby cause both roll shaft supporting means to swing in unison away from the platen during further rotation of the rock shaft.
- 50 11. In a typewriting machine, the combination of a platen carriage, a platen rotatably mounted on the carriage, a cast-off rock shaft journalled on the carriage, tandem feed rolls, independent supporting means 55 for the rolls located at the same side of the rock shaft and pivotally held at one end to the shaft to swing about the shaft, said supporting means being interlocked with each other against relative movement longitudinally of the shaft, means on the rock shaft for holding one of said supporting means against movement longitudinally of the shaft and adapted to lock said supporting means to the shaft to rock therewith 60 65 away from the platen when the shaft is

rotated in one direction; the other roll supporting means being rockable away from the platen by the supporting means which is directly locked to the shaft after a predetermined movement of the rock shaft. 70

12. In a typewriting machine, the combination of a platen carriage, a platen rotatably mounted on the carriage, a cast off rock-shaft journalled on the carriage, front and rear feed rolls, independent superposed supporting means carrying the rolls at their forward ends and interlocked with each other against relative movement longitudinally of the shaft, the supporting means for the rear roll being pivotally connected 75 at its rear end with the rock shaft and the supporting means for the front roll having a pivotal and limited up-and-down sliding connection at its rear end with the rock shaft, means on the rock shaft for swinging the rear roll supporting means downwardly away from the platen and causing the same to first depress the rear end of the front roll supporting means and then swing said front roll supporting means about the 80 rock shaft. 85

13. In a typewriting machine, the combination of a platen carriage, a platen rotatably mounted on the carriage, a cast off rock-shaft journalled on the carriage, front and rear feed rolls, independent superposed supporting means carrying the rolls at their forward ends and interlocked with each other against relative movement longitudinally of the shaft, the supporting means for the rear roll being pivotally connected 95 at its rear end with the rock-shaft and the supporting means for the front roll having a pivotal and limited up-and-down sliding connection at its rear end with the rock shaft, means on the rock shaft for swinging the rear roll supporting means downwardly away from the platen and causing the same to first depress the rear end of the front roll supporting means and then swing said front roll supporting means about the rock shaft. 100

14. In a typewriting machine, the combination of a platen carriage, a platen rotatably mounted on the carriage, a cast off rock-shaft journalled on the carriage, front and rear feed rolls, independent superposed supporting means carrying the rolls at their forward ends and interlocked with each other against relative movement longitudinally of the shaft, the supporting means for the rear roll being pivotally connected 110 at its rear end with the rock shaft and the supporting means for the front roll having a pivotal and limited up-and-down sliding connection at its rear end with the rock shaft, means on the rock shaft for swinging the front roll supporting means about the rock shaft, and spring urged means on the platen pressing the front roll supporting means toward the platen against the rear roll supporting means. 115

the rear roll supporting means downwardly away from the platen and causing the same to first depress the rear end of the front roll supporting means and then swing said front roll supporting means about the rock shaft, and spring urged means on the carriage loosely engaging under the front roll supporting means intermediate the front and rear rolls and pressing the front roll supporting means upwardly against the rear roll supporting means.

15. In a typewriting machine, a platen carriage, a platen rotatably mounted on the carriage, tandem feed roll shafts, rolls on said shafts, a cast-off rock shaft journaled on the carriage, a pair of members pivotally held to said rock shaft supporting the rear roll shaft at their forward ends, a pair of members engaging under the first pair of members and supporting the front roll shaft at their forward ends and having their rear ends bent to form downwardly facing hooks through which the rock shaft extends, and means on the rock shaft interlocked with the rear roll shaft supporting members to permit the same to have a limited pivotal movement on the rock shaft when the rock shaft is stationary and to lock the same to the rock shaft when the shaft is rotated.

20. 16. In a typewriting machine, a platen carriage, a platen rotatably mounted on the carriage, tandem feed roll shafts, rolls on said shafts, a cast-off rock shaft journaled on the carriage, a pair of members pivotally held to said rock shaft supporting the rear roll shaft at their forward ends, a pair of members engaging under the first pair of members and supporting the front roll shaft at their forward ends and having their rear ends bent to form downwardly facing hooks through which the rock shaft extends, means on the rock shaft interlocked with the rear roll shaft supporting members to permit the same to have a limited pivotal movement on the rock shaft when the rock shaft is stationary and to lock the same to the rock shaft when the shaft is rotated, means on the carriage loosely engaging under the front roll shaft supporting members at points intermediate the front and rear rolls, and a spring for pressing said means upwardly against said members.

17. In a paper feed mechanism, the combination of a platen, a cast-off shaft, tandem feed-roll shafts, feed rolls on said tandem shafts, means for rocking said cast-off shaft, independent supports for said tandem feed-roll shafts, pivotal connections between said shaft supports and the cast-off shaft whereby either feed-roll shaft may move away from the platen when the cast-off shaft is stationary, spring-urged means connected with the support for one shaft for pressing the same toward the platen and against the other shaft support, and a con-

nection between the cast-off shaft and said other shaft support for forcing both supports away from the platen.

18. In a paper feed mechanism, the combination of a platen, a cast-off shaft, means for rocking said shaft, two interconnected sets of rock arms extending in the same direction from said shaft and movable independently thereof toward and from the platen, tandem feed-roll shafts supported by said two sets of rock arms, rolls on said tandem shafts, connections between the cast-off shaft and one set of rock arms for swinging both interconnected sets of arms away from the platen when the cast-off shaft is rocked, a pressure distributing member connected with one of said sets of rock arms intermediate the feed-roll shafts for pressing both interconnected sets of arms toward the platen, and a spring-urged support on which said member is tiltably mounted substantially midway its ends to rock about an axis extending transversely of the platen.

19. In a paper feed mechanism, the combination of a platen, a cast-off shaft extending longitudinally of the platen at the rear of said platen, a plurality of pairs of forwardly extending independently rockable arms pivotally held at their rear ends to the cast-off shaft, a plurality of rear feed-roll shafts each supported by one of said pairs of arms, a plurality of pairs of forwardly extending members having pivotal and up-and-down sliding connections with the cast-off shaft at their rear ends and loosely engaging under the rock arms, a plurality of front feed-roll shafts each supported by one of said pairs of members, feed rolls on the front and rear feed-roll shafts, a plurality of pressure-distributing members each engaging under one of said pairs of members intermediate the feed-roll shafts, yieldable means for supporting said members to move at either or both ends away from the platen, and means on the rock shaft for causing the rock arms to rock therewith away from the platen.

20. In a paper feed mechanism, the combination of a platen carriage, a platen on the carriage, a plurality of rear feed-roll shafts, a plurality of front feed-roll shafts, feed-rolls on all the shafts, independent pairs of rock arms each supporting one shaft and all pivotally supported on the carriage at the rear of the platen, said front feed-roll shaft supporting arms having an up-and-down sliding movement on their pivotal support and normally engaging the under side of the rear feed-roll shaft supporting arms, means for yieldably pressing the front feed-roll shaft supporting arms upwardly against the rear feed-roll shaft supporting arms, and means for rocking all the rear feed-roll shaft supporting arms downwardly about their pivots.

21. In a paper feed mechanism, the combination of a platen carriage, a platen on the carriage, a rock shaft journalled on the carriage, means for rocking said rock shaft, 5 independent arms each having a direct pivotal and up-and-down sliding connection with the rock shaft, a feed roll supported by said arms, means for independently pressing the arms toward the platen, and means on said rock shaft holding said arms against movement longitudinally of the rock shaft and adapted to swing the arms away from the platen about the axis of the rock shaft 20 when said shaft is rocked in one direction. 25

22. In a paper feed mechanism, the combination of a platen carriage, a platen on the carriage, a rock shaft journalled on the 15

carriage, means for rocking said rock shaft, independent arms each having a direct pivotal and up-and-down sliding connection with the rock shaft, a feed roll supported by said arms, means for independently pressing the arms toward the platen, and means on said rock shaft holding said arms against movement longitudinally of the rock shaft and adapted to swing the arms away from the platen about the axis of the rock shaft 25 when said shaft is rocked in one direction.

This specification signed this sixth day of November, A. D. 1918.

FRANK H. ARMSTRONG.
